UNITED STATES PATENT OFFICE.

HUGH MISCAMPBELL, OF DULUTH, MINNESOTA.

HYDRATOR.

Application filed December 20, 1923. Serial No. 681,717.

This invention relates to a combination lime hydrator and mortar making device and has special reference to the making of complete dry mortar such as used for plastering or the like.

The principal object of the invention is to provide a simple and compact machine for the production of a finished dry mortar product from hydrated lime, the same being accomplished simultaneously with the hydration of the lime.

Another object of the invention is the provision of means whereby either hydrated lime or dry mortar may be made with the machine, or the latter product accomplished by the machine without simultaneous hydration of the lime as desired.

Other objects and advantages of the invention will appear in the further description thereof.

Referring now to the accompanying drawings forming part of this application:

Figure 1 is a side elevation of the upper half of the machine, partly broken away, showing the lime hydrating apparatus and the hopper in which the other materials are added when the machine is used in the manufacture of mortar; and

Figure 2 is a similar view of the lower part of the machine, showing the conveyors, cooler, elevators, etc.

Referring particularly to Figure 1 of the drawings the stack of the hydrator is shown at 1, and the weighing and charging apparatus at 2, through which the material is weighed and fed to the hydrator or primary mixer. A water supply is also provided in any well known manner, it not being considered necessary to illustrate the same here, as this form of lime hydrator is old in the art.

The mixer proper is illustrated at 3, for the interior construction of which and the arrangement of stirring devices thereof, reference is had to my former United States Patent No. 1,398,238 of November 29th, 1921; all the objects and advantages of which are derived in the invention. A suitable driving mechanism is provided such as illustrated at 4 for rotating the mixer, and the operation and control of the interior mixing devices may be readily effected by the control mechanism illustrated at 5.

The mixer 3 is mounted upon the roller bearing base 6 supported upon a suitable

fabricated steel base or bed 7 which rest upon a floor 8.

Concentrically below the base 6 and below the floor is the hopper or bin 9, the same being provided at its lower end with a suitable feeding device 10, the office of which is to feed the material being mixed to the cooling drum 11 in the proper quantities; the base of the feeding device being of course connected in any suitable manner to the upper end of the cooling and mixing drum. This drum is provided with a central longitudinal shaft 12 the same having securely fixed thereto a number of paddles or mixing blades 13, they being for the purpose of further mixing and agitating the material as it slowly passes through the cooler, and the shaft 12 is provided with any desired means for rotation, for example the pulley and gear connection indicated at 14. The material then passes from the cooler 11 into one end of the spiral conveyor 15 which leads through a pulverizer and air separator, of any suitable type, such as indicated at 16, and the other end of the conveyor 15 communicates with a bucket elevator 17, which may lead to a bagging machine, or bins for storing of the material.

To provide for the manufacture of mortar, I have shown the hopper 18 supported by the floor 8 in which the desired additional material such as hair and the like are placed. In the lower end of the hopper is installed any form of agitator 19 through which the material must pass to the feeder 20, the same being directly connected to said hopper.

The feeder 20 is for the purpose of regulating the amount of materials passing therethrough in the right proportion with the amount of hydrated lime passing through the feeder 10. The feeder 20 communicates with one end of the spiral conveyor 21 which conducts the materials therethrough and empties them into the upper end of the cooling drum 11 where they are mixed with the lime hydrate and together pass through the cooler into the second conveyor 15 and to the bucket elevator 17, from thence to the place of storage.

The conveyor 15, as above described, also communicates with the pulverizer and separator 16, said communication being controlled by the slide indicated at 22, so that when mortar is being made, the slide may be closed, thus forcing all of the material

through the conveyor 15 to the bucket elevator 17; but when hydrated lime only is being produced the slide 22 may be opened, thus allowing the hydrate to drop into the pulverizer and air separator and subsequently take up the bucket elevator 23 to a storage hopper or bagging machine, as desired.

It is well known in the art that other material such as cement is sometimes incorporated within mortar and in which event it is obvious that the same may be supplied to the hopper 18 with the hair and in any desired quantities so that it, together with the hair, become thoroughly mixed during the travel of the conveyor 21 and then more thoroughly incorporated in the mix as it continues through the machine.

In the production of hydrated lime only the conveyor 21 may be shut off, as no material would pass therethrough, and the regular process of hydration and air separation take place as previously described.

Having thus described my invention, what I claim and desire to secure by Letters Patent, is:

The combination with a lime hydrator, of means directly associated therewith whereby either finished dry mortar or dry hydrated lime may be continuously supplied from said means, and a pulverizer intermediate of the mortar and hydrator discharges.

In testimony whereof I hereunto affix my signature.

HUGH MISCAMPBELL.
